UNITED STATES PATENT OFFICE.

LE ROY R. BLADES, OF CHICAGO, ILLINOIS, ASSIGNOR, BY DIRECT AND MESNE ASSIGNMENTS, TO FRANK J. GANDY.

AUXILIARY INTAKE AIR VALVE.

Application filed August 11, 1923. Serial No. 656,932.

To all whom it may concern:

Be it known that I, LE ROY R. BLADES, a citizen of the United States, residing at Chicago, in the county of Cook and State of Illinois, have invented certain new and useful Improvements in Auxiliary Intake Air Valves, of which the following is a description.

My invention belongs to that general class 10 of inventions known as valves, and relates more particularly to an auxiliary intake air valve to be used in connection with internal combustion engines for admission of air to the ingoing charge, as for example, to the intake manifold at a point between the intake ports and the throttle valve.

The invention has among its objects the production of a device of the kind described 20 that is simple, convenient, compact, durable, efficient, automatic in operation and satisfactory for use wherever found applicable.

It has particularly as an object the production of an automatic valve which will admit the proper amount of air and automatically control the admission of air to conform 25 with the working condition of the engine.

More particularly it has as an object the production of a device which will not admit air to the intake when the engine is starting or idling or operating at low speed, but will permit the admission of air when 30 the engine is speeded up.

Many other objects and advantages of the 35 construction herein shown and described will be obvious to those skilled in the art from the disclosures herein given.

To this end my invention consists in the 40 novel construction, arrangement and combination of parts herein shown and described, and more particularly pointed out in the claims.

In the drawings, wherein like reference 45 characters indicate like or corresponding parts,

Fig. 1 is a side elevation of an engine showing my device installed on the manifold;

Fig. 2 is a side elevation of my device; 50 Fig. 3 is a sectional view taken substantially on line 3—3 of Fig. 2;

Fig. 4 is a sectional view taken substantially on line 4—4 of Fig. 2;

Fig. 5 is a sectional view taken substantially on line 5—5 of Fig. 2;

Fig. 6 is a sectional view of a portion of the device similar to Fig. 3 and showing the parts in their changed positions; and

Fig. 7 is a sectional view similar to Fig. 3, showing a slight modification.

Referring to the drawings, in which the preferred embodiment of my invention is shown, 1 represents any type of gas engine provided with the usual carburetor 2 and fuel intake manifold 3, 4 representing the throttle or butterfly valve ordinarily employed. The engine, carburetor, manifold, etc., are typical of any of the well known constructions and illustrate the application of my improved device.

It is well known to those skilled in the art that when running at higher speeds a certain amount of air may be admitted to the intake manifold without decreasing the efficiency of the charge, but on the contrary, increasing its efficiency. At low speeds, or when starting or idling, it is not desirable, however, to admit air to the manifold, as the same affects the operation of the engine and makes starting hard or may cause the engine to kill. When the engine is running at low speed or idling, there is a greater vacuum in the manifold than when the throttle is opened up, and my device is automatically operable so that the greater the vacuum in the manifold, the less air is admitted, the same being generally so adjusted that in starting and idling or at low speeds, no air is admitted through the device.

As shown, 6 represents a part mounted on the manifold 3 for example, the same being provided with a shank 7 for engagement with a threaded hole through the manifold. The part 6 is provided with a tubular extension portion or sleeve 8 and an outer shell 95 or casing 9 arranged as shown, the latter being preferably threaded on the portion 6. As shown, part 6—8 is constructed with a shoulder of reduced diameter, as indicated at 10, so as to provide a space between the parts 8 and 9. Slidably or telescopically carried by part 8 is a valve member or

- sleeve 11, which I preferably slot adjacent its outer end to form openings 12, as indicated. The openings may be of the desired size and shape and arranged as desired.
- 5 The valve is also provided at its outer end with a head or closure member 13 having a face part 14, which may seat upon the end of part 8 when the valve is moved to its inner or closed position.
- 10 Arranged to cooperate with the valve is a spring 15, which tends to normally move and maintain the valve in the position shown in Fig. 3 or open so that air may be admitted through the opening 12 to the tubular bored part 6 and be discharged into the manifold, or other point.
- 15

I have shown a cap 5 arranged on the part 9 adapted to be adjusted so that the downward travel of the valve 11 may be controlled and limited by adjusting the cap. A collar 18 may be arranged, as shown, which serves as an abutment with the cap, and when tightened against the cap, locks the same against accidental displacement.

20

25 The cap is provided with one or more openings 16 therethrough of the desired size and shape, and if preferred, a piece of wire gauze or the like 17 may be arranged over the openings to prevent the admission of dust and dirt.

30

I have illustrated in Fig. 3 an annular adjustable abutment 19 for the end of the spring 15, the same being provided with a projecting part 20 which extends to the exterior of the shell 9 and cooperates with the lock rings 21 and 22. By adjusting the rings 21 and 22 to move the member 19, the tension of the spring 15 may be varied as desired.

35

40 While not essential, if preferred, a stem 23 may be projected through the casing 5, the same permitting manipulation of the valve without removing the cap, and if the same is provided with a scale, it will serve to indicate the operations of the valve.

45

In the construction shown in Fig. 7, in place of the adjustable abutment 19, I have illustrated one or more washers 24 to be inserted as desired to provide adjustment or regulation of the spring.

50

55

60

65

In use, the spring is so adjusted that when the motor is starting, idling, or traveling at low speed, the increased vacuum in the manifold will tend to move the valve 11 to its closed position so that no air is admitted therethrough to the manifold, but as the engine is speeded up and the vacuum decreases, the spring 15 will tend to move the valve to admit a limited amount of air into the manifold. Further increasing the speed in the engine by opening the butterfly valve 4 will cause a still further effective opening in the valve. Immediately upon idling down, however, the valve will move toward its closed position.

Obviously, with different types, sizes and engine capacities, my device would be adjusted by means of the cap 5 and the varying of the tension of the spring to produce the most satisfactory and efficient results.

70

75

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

80

What I claim as new and desire to secure by Letters Patent is:

85

90

95

1. In combination with an intake manifold, air supply means communicating therewith and operable by suction therein to vary the amount of air admitted therethrough, said means comprising a sleeve fixed to said manifold and opening thereinto, a sleeve slidably in said first-mentioned sleeve and having a longitudinal slit adjacent its outer end, a casing around said sleeves and having a port therethrough, said casing comprising a plurality of members adjustably secured to each other, and a spring for yieldingly holding said inner sleeve in its normal position whereby the increase of suction in the manifold will move said inner sleeve against the action of the spring to vary the effective size of the slit opening.

100

105

2. In combination with an intake manifold having a throttle valve therein, a sleeve adapted to be fixed to said manifold and opening thereinto, a valve slidably fitting in said sleeve and having an elongated opening at one end, means for normally pressing said valve outwardly of said sleeve, and a casing enclosing said sleeve and valve and having a port through which all air entering said opening must flow, said valve being actuated by the suction in said manifold.

110

115

120

125

3. In combination with an intake manifold, air supply means communicating therewith and comprising a sleeve fixed thereto and communicating therewith, a valve telescopically fitting into said sleeve from one end and having its other end slotted, a closure across the slotted end of said valve, a casing enclosing said sleeve and valve and providing an abutment for said closure means in one direction and having a port through its wall communicating with said slot, a spring between said casing and sleeve and bearing at one end against said closure means to tend to yieldably force the valve away from said fixed sleeve, and means movably carried by said casing and adapted to abut against the other end of said spring for adjusting the tension thereof.

130

4. In combination with an intake manifold, a sleeve adapted to be fixed to said

manifold and opening thereinto, a valve slidably journaled by said sleeve and having an elongated opening at one end, means for normally pressing said valve outwardly of 5 said sleeve, a casing enclosing said sleeve and valve and having a port through which all air entering said opening must flow, said

valve being actuated by suction in said manifold, and manually operable means for controlling the effective size of the port. 10

In testimony whereof, I have hereunto signed my name.

LE ROY R. BLADES.
